UNITED STATES PATENT OFFICE.

ALFRED PESOLA, OF BERKELEY, CALIFORNIA.

NON-STRETCH LINING FOR GARMENTS.

1,184,375.

Specification of Letters Patent. Patented May 23, 1916.

Application filed July 8, 1914. Serial No. 849,713.

To all whom it may concern:

Be it known that I, ALFRED PESOLA, a subject of the Emperor of Russia, residing at 909 Pardie street, Berkeley, in the county 5 of Alameda and State of California, have invented certain new and useful Improvements in Non-Stretch Linings for Garments, of which the following is a specification.

10 This invention relates to improvements in garments and more particularly to means in connection therewith to prevent bagging at those portions subject to stretching.

15 The principal object of my invention is to provide a simple concealed device, which is part of the garment and which prevents stretching of the material in a diagonal direction and therefore what is generally termed bagging.

20 Another object of my invention is to provide a device of this character which will offer no inconvenience to the wearer, which is simple in construction, inexpensive in application and effective in operation, and 25 while I have shown the same attached to the knee of trousers it will be understood that it may also be applied to sleeves, the skirts of ladies' garments and any other garment which is subject to stretching.

30 With these and other objects in view my invention consists in the novel construction as herein set forth and as more specifically pointed out in the appended claim.

Reference should be had to the accompanying drawing forming a part of this specification wherein,

35 Figure 1 is a view in elevation of a pair of trousers with a portion broken away to disclose the device of my invention and the 40 interior thereof. Fig. 2 is an enlarged view in rear elevation of a portion of the device used to prevent stretching. Fig. 3 is an enlarged view in cross section on the line 3—3, Fig. 1.

45 Referring to corresponding parts by the same numerals of reference, 1 denotes a pair

of trousers composed of the front piece 2 and the rear piece 2'.

3 denotes a piece of fabric which is so woven as to have comparatively little 50 stretch, this member being cut approximately the same shape as the front piece 2 and is further reinforced against stretching by means of a plurality of diagonal strips 4, 5 and 6. These strips are formed 55 of fabric, which has almost no tendency to stretch in longitudinal direction. The strips 4 and 5 are attached to 3 so as to extend diagonally from opposite corners while the strips 6 are attached in a radial direction 60 from the intersection of 4 and 5, thus the piece 3 is thoroughly reinforced and held against stretching in any direction. In sewing together the trousers the pieces 3 are attached in the side seams of the same as 65 shown in Fig. 3. The principal cause of the bulging at the knees is due to the fact that the fabric exposed to the front part of the leg is caused to stretch in diagonal direction or at an angle to the threads of the weave, 70 which with this device is entirely prevented.

It will, of course, be understood that while I have shown the preferred embodiment of my invention minor details and arrangement of the diagonal strips may be made without 75 departing from the scope of the claim.

What I claim as new and wish to cover by Letters Patent is:—

The combination with a garment having side seams, a lining in said garment held in 80 said side seams, a plurality of radial disposed reinforcing strips attached to said lining and converging at the point where pressure takes place against said garment.

In testimony whereof I affix my signature 85 in presence of two witnesses.

ALFRED PESOLA.
